United States Patent Office

Des. 207,281
Patented Mar. 28, 1967

207,281

CALCULATING MACHINE

Karl T. Baughman, Evanston, Ill., assignor to Sears, Roebuck and Co., Chicago, Ill., a corporation of New York

Filed Sept. 13, 1965, Ser. No. 86,968

Term of patent 14 years

(Cl. D64—11)

Fig. 3.

Fig. 2.

Fig. 4.

FIG. 1 is a front perspective view of a calculating machine showing my new design;

FIG. 2 is a side elevational view thereof, the side opposite thereto being similar in appearance;

FIG. 3 is a front elevational view thereof, and

FIG. 4 is a rear elevational view thereof.

The essential features of the design reside in the parts shown in full lines.

I claim:

The ornamental design for a calculating machine, as shown and described.
